UNITED STATES PATENT OFFICE

GEORGE E. JANOSIK, OF ELYRIA, OHIO

RAILWAY SAFETY CROSSING

Application filed June 7, 1929. Serial No. 369,181.

The present invention relates to an apparatus for preventing accidents at railroad crossings, and has for its prime object to provide means for preventing an automobile or other vehicle from crossing a railroad track when a train is approaching.

Another very important object of the invention resides in the provision of an apparatus of this nature which is automatic in its 10 operation, simple in its construction, strong and durable, thoroughly efficient and reliable in use, and otherwise well adapted for the purpose for which it is designed.

With the above and numerous other objects 15 in view as will appear as the description proceeds, the invention resides in certain novel features of construction and in the combination and arrangement of parts as will be hereinafter more fully described and claimed.

20 In the drawings:

Figure 1 is a top plan view of my railway safety crossing.

Figure 2 is a longitudinal vertical section taken substantially on the line 2—2 of Figure 25 1.

Figure 3 is a longitudinal vertical section taken substantially on the line 3—3 of Figure 1.

Figure 4 is a top plan view showing the 30 ledge removed.

Figure 5 is a diagrammatic view showing the electrical features.

Figure 6 is a fragmentary perspective view of one end of the platform.

Figure 7 is a sectional view taken substantially on the line 7—7 of Figure 3.

Figure 8 is a perspective view of one block.

Figure 9 is a perspective view of the other 40 block.

Figure 10 is a perspective view of a vertical sliding bar.

Figure 11 is a perspective view of a lever adapted to be associated with said bar.

Figure 12 is a perspective view of a sliding 45 bar movable on an incline.

Referring to the drawings in detail, it will be seen that the numeral 5 denotes railroad tracks and numeral 6 a roadway crossing the track. On opposite sides of the track are pits 7, one to one side of the roadway

and the other to the other side of the roadway. My improved apparatus are associated with these pits, and one apparatus will be described in detail, as this will be sufficient for a correct understanding of both. Across 55 an intermediate portion of the pit is a concrete foundation member 9, from which rises a rocker bracket 10.

This member 9 is located closely to the end of the pit remote from the track 5. The platform 11 is rockable on the rocker bracket 10 and has a weight 12 at one end remote from the railroad track, so as to normally hold the platform in the position shown in Figures 2 and 3 with the weights resting on a shelf 14 and an extension on the platform 15 resting on the roadway. A ledge 16 forms a part of the roadway and extends over the end of the pit 7 adjacent the railroad track and the adjacent end of the platform 11 is normally flush 70 therewith.

A foundation member 17 is located in the pit 7 at the end adjacent the railroad track and has mounted thereon casings 18, with the bolts 19 slidably therethrough and actuatable by links or extensions 20 connected to cross rods 21 with which a link 22 is engaged, oppositely connected with an electric motor 23, which may be energized through a circuit 24 shown in Figure 5, by the wheel of an oncoming train, engages the circuit 60 closer 25 of suitable construction.

Springs 26 normally hold the bolts extended to engage under the adjacent end of the platform 11. Standards 27 rise from the foundation member 17 and rockably receive the intermediate portion of the angular levers 28, having ends extending under the platform 65 engageable with anti-friction rollers 29 and with their ends longitudinally slotted as at 30.

A boss 31 is mounted on the ledge 16 and tapers from an intermediate portion toward the track as is indicated at *a* and also tapers from said intermediate portion in the other direction as is indicated at *b* and said intermediate portion is denoted by the letter 70 *c* and has a pair of vertical openings 32 therein. Bars 33 are slidable in these vertical openings 32 and adjacent their lower ends are provided with slots 34 and at their lower ends with eyes 35. Pins 36 extend in slots

34 and 30 to provide pin and slot connections between the levers 28 and the bars 33. Springs 38 are anchored to the eyes 35 and to a foundation member 39 at the bottom of the pit for normally holding the bars downwardly and the free ends of the levers in engagement with the anti-friction rolls 29. A block 40 is mounted on the platform 11 above the rocker bracket 10 and tapers from an intermediate portion c' as is indicated at a' , away from the trackway while the other end tapers toward the trackway as is indicated by c' . Inclined openings 41 extend from the top surface of the upper end of the portion c' to the bottom surface of the portion a' in parallelism with each other and in substantial parallelism with the upper surface of the portion a' . Bars 42 are slideable through the openings, terminating at one end in eyes 43 and adjacent the other end being formed with slots 44. A pin 45 through the intermediate portion c' extends through the slots 44, thereby limiting the movement of these bars 42. Springs 46 are engaged with the eyes 43 and anchored on the platform 11 to hold the bars inwardly of the openings.

A pair of tables 48 are engaged with the bars 42 and with the bars 33 and extend between the two blocks 31 and 40 in a taut condition.

If no train is approaching and the bolts 19 are properly set in their normal position, an automobile riding on the platform may pass freely there over. However, should the train be approaching and the switch 25 be closed to cause energization of the motor 23, it will be seen that the bolts 19 will be withdrawn so that when an automobile rides onto the platform 11, the platform will tilt and the front axle will engage on the cables 38 and the ends of these cables adjacent the block 31 will be raised because the platform will rock the lever 28 thereby pushing the bars 33 upwardly, placing the cables on an incline upwardly in a direction of movement of the automobile, so that the automobile will be brought to a gradual but positive stop and be unable to cross the railroad track.

It is thought that the construction, operation, utility and advantages of this invention will be now quite apparent to those skilled in this art, without a more detailed description thereof.

The present invention has been disclosed in detail merely for the purpose of exemplification, since in actual practice it attains the features of advantage enumerated as desirable in the statement of the invention and the above description.

It will be apparent that changes in the details of construction and in the combination and arrangement of parts may be resorted to without departing from the spirit or scope of the invention as hereinafter claimed or sacrificing any of its advantages.

Having thus described my invention, what I claim as new is:

1. A structure of the class described including a runway having a pit formed therein, a platform, means for rockably mounting the platform above the pit, means for normally holding the platform flush with the runway, a cable, means for holding the cable along the platform so that a machine causing the tilting of the platform would rest its axle on the cable and be retarded thereby, a bolt for preventing tilting of the platform, and means for retracting the bolt. 70

2. A structure of the class described comprising a runway having a pit formed therein, a platform, means for rockably mounting the platform above the pit, means for normally holding the platform flush with the runway, a cable, means for holding the cable along the platform so that a machine causing the tilting of the platform would rest its axle on the cable and be retarded thereby, a bolt for preventing tilting of the platform, and means for retracting the bolt, and means for causing the end of the cable in the direction from which the machine is approaching to be raised when the platform is tilted. 80

3. A structure of the class described including a runway having a pit formed therein, a platform, means for rockably mounting the platform above the pit, means for normally holding the platform flush with the runway, a cable, means for holding the cable along the platform so that a machine causing the tilting of the platform would rest its axle on the cable and be retarded thereby, a bolt for preventing tilting of the platform, and means for retracting the bolt, a ledge extending from the runway to one end of the platform, a bar slideable vertically through the ledge and having one end of the cable attached thereto, and means for raising the bar when the platform is tilted. 95

4. An apparatus of the class described including, in combination, a runway formed with a pit, a platform, means for rockably mounting the platform on the pit, a ledge extending over one end of the pit beneath the platform, a block on the platform, a block on the ledge, a cable, resilient means for anchoring the cable in the block on the platform, a bar slideable vertically through the ledge and the block thereon, said cable being attached to the last mentioned bar, and means for raising the last mentioned bar when the platform is tilted downwardly. 110

5. An apparatus of the class described including, in combination, a runway formed with a pit, a platform, means for rockably mounting the platform on the pit, a ledge extending over one end of the pit beneath the platform, a block on the platform, a block on the ledge, a cable, resilient means for anchoring the cable in the block on the platform, a bar slideable vertically through the ledge and 120

the block thereon, said cable being attached to the last mentioned bar, a lever pivotally mounted in the platform having one end under the platform, the other end having a pin and slot connection with the last mentioned bar, so that when the platform is tilted, the said bar is moved upwardly.

6. An apparatus of the class described including, in combination, a runway formed with a pit, a platform, means for rockably mounting the platform on the pit, a ledge extending over one end of the pit beneath the platform, a block on the platform, a block on the ledge, a cable, resilient means for anchoring the cable in the block on the platform, a bar slidably vertically through the ledge and the block thereon, said cable being attached to the last mentioned bar, a lever pivotally mounted in the pit having one end under the platform, the other end having a pin and slot connection with the last mentioned bar, so that when the platform is tilted, the said bar is moved upwardly, spring pressed means urging said bars downwardly.

25 7. An apparatus of the class described including in combination, a runway formed with a pit, a platform, means for rockably mounting the platform on the pit, a ledge extending over one end of the pit beneath the platform, a block on the platform, a block on the ledge, a cable, resilient means for anchoring the cable in the block on the platform, a bar slidably vertically through the ledge and the block thereon, said cable being attached to the last mentioned bar, a lever pivotally mounted in the pit having one end under the platform, the other end having a pin and slot connection with the last mentioned bar, so that when the platform is tilted, the said bar is moved upwardly, spring pressed means urging said bars downwardly, said resilient anchoring means comprising a bar slidably in an opening in the block on the platform, spring means entering the last mentioned bar, said cable being attached to said last mentioned bar.

8. An apparatus of the class described including in combination, a runway formed with a pit, a platform, means for rockably mounting the platform on the pit, a ledge extending over one end of the pit beneath the platform, a block on the platform, a block on the ledge, a cable, resilient means for anchoring the cable in the block on the platform, a bar slidably vertically through the ledge and the block thereon, said cable being attached to the last mentioned bar, a lever pivotally mounted in the pit having one end under the platform, the other end having a pin and slot connection with the last mentioned bar so that when the platform is tilted, the said bar is moved upwardly, spring pressed means urging said bars downwardly, said resilient anchoring means comprising a bar slidably in an opening in the block on

the platform, spring means anchoring the last mentioned bar, said cable being attached to said last mentioned bar, a pin and slot means associated with said last mentioned bar and said last mentioned slot to limit the movement of said last mentioned bar.

In testimony whereof I affix my signature.

GEORGE E. JANOSIK.
